UNITED STATES PATENT OFFICE.

CHARLES R. HULTGREN, OF CHICAGO, ILLINOIS, ASSIGNOR TO S. KARPEN & BROS., OF CHICAGO, ILLINOIS, A CORPORATION OF WEST VIRGINIA.

SOFA BED.

Application filed April 9, 1926. Serial No. 100,899.

This invention relates particularly to a combination sofa and bed; and the primary object of the invention is to provide a cheap and simple construction which is well adapted to its purpose.

The invention is illustrated in its preferred embodiment in the accompanying drawings, in which—

Fig. 1 represents a broken vertical sectional view showing the structure in bed-form; Fig. 2, a broken plan sectional view taken as indicated at line 2 of Fig. 1; Fig. 3, a broken plan sectional view taken as indicated at line 3 of Fig. 1; Fig. 4, a view similar to Fig. 1, but showing the front bed-section collapsed and in readiness to be shoved into the folded position; Fig. 5, a broken plan section taken as indicated at line 5 of Fig. 4; Fig. 6, a broken vertical section taken as indicated at line 6 of Fig. 1; Fig. 7, a broken section taken as indicated at line 7 of Fig. 1 and showing a guide-bar employed; and Fig. 8, a broken vertical sectional view taken as indicated at line 8 of Fig. 4.

In the construction illustrated, A designates the main frame of the sofa-bed; B, a rear bed-section fixedly mounted in said frame and which is adapted to serve also as a seat; and C, a front bed-section collapsibly mounted upon a sliding frame C' which is connected with guides C² (one shown), with which the lower portion of the main frame A is provided.

The main frame A may be of any suitable construction. In the illustration given, it comprises end-standards 1 (one shown) connected by longitudinal members 2 which serve as the base for the bed-section B.

The bed-section B is shown as comprising conical springs 3 supported upon the base 2 and affording a foundation for a mattress, or cushion, (not shown).

The front bed-section C is shown as comprising a rectangular frame 4 which supports conical springs 5 affording a foundation for a mattress, or cushion, (not shown). The sliding supporting frame C' for the front bed-section consists of a rectangular frame composed of end-members 6 and longitudinal connecting members 7 and 8. The front member 7 has secured thereto a front piece 9 which is adapted to be housed beneath the front member 2 of the main frame when the structure is in sofa-form.

The end-members 6 of the sliding frame

C' have secured thereto guide-bars 10 (Fig. 7) which extend parallel with the end-members 6 and secured thereto by rivets 11. An intervening spacer member 12 preferably is employed. The spacer, or spacers, 12 rests 60 on the guide C² and the guide-bar 10 is disposed back of the guide C², as indicated by dotted lines in Fig. 6. The slide is held in the guide by means of a bar 13 which is secured to the end-member 1.

The bed-section C has its frame portion 4 mounted on parallel links 14 and 15 which, it will be understood, are duplicated at the two ends of the structure. The lower ends of said links are pivotally connected with the 70 end-member 6 of the slidable frame C'. The upper portions of said links are connected by pivots 16 with slides 17 mounted on the end-members of the frame 4. The slides 17 are connected by a link 18 whose end-portions are 75 connected with the pivots 16.

The front links, or arms, 15 are provided at their upper ends with extensions 19 which serve as handles. The extensions 19 are shown connected by a rod or shaft, 20. The 80 extensions 19 project forwardly and upwardly, assuming the structure to be in bed-form.

The frame 4 of the bed-section C is equipped with depending lugs 21 with which are connected levers 21^a which are pivotally 85 connected at 22 with depending lugs carried by the front portions of the end-members 6 of the frame C'. Counterbalancing springs 23 connect the short arms or legs of the levers 21 with the sliding frame C'.

A stop-bar 24 is secured to the rear member 8 of the frame C' and serves to limit the forward movement of the frame C' by striking stops 24^a.

When the structure is in bed-form, the 95 links 14 preferably incline forwardly somewhat, so that there will be no danger of the front bed-section collapsing under the weight of an occupant. The rear links 14 are connected with the end members of the 100 frame C' by pivots 25. The front links 15 are pivotally connected with the end-members 6 through the medium of a longitudinal bar 26, which preferably is of square cross-section. As shown in Fig. 8, the end portion 105 of the bar 26 enters a squared perforation in a boss 15^a with which the link, or lever, 15 is provided. The boss is provided with a circular bearing portion 15^b which is free to turn within a bearing perforation with which 110

the frame-member 6 is provided. The boss 15^a is confined between the vertical flange of the member 6 and a collar 27 on the bar 26, said collar being held in place by lugs 28 formed by cutting or striking the metal at the corners of the bar.

The manner in which the improved structure operates will be readily understood from Fig. 1. An operator may grasp the handle 10 20 and swing the link 15 rearwardly. This results in causing the slides 17 to move rearwardly and lower the front bed-section to the position shown in Fig. 4. The collapsed bed-section may then be shoved rearwardly and 15 housed within the main frame beneath the rear bed-section. The reverse operation of converting the structure from sofa-form to bed-form is obvious.

It will be understood that the parts may 20 be suitably separated so that space will be provided between the front bed-section and the superposed rear bed-section for bedding, if desired; also, that the rod, or handle, 20, will, in the collapsed condition of the front 25 bed-section, project over any bedding which may be left upon the front bed-section C. Also, it will be understood that suitable mattresses, or cushions, may be employed in connection with the structure. The fixed bed-section B serves as a seat when the structure 30 is used for sofa purposes, the cushions being superposed upon the springs 3.

When the structure is in extended position, the front rail of the frame 4 may be disposed 35 above the front piece 9. When the collapsing action occurs, the levers 21^a cause a short rearward movement of the frame 4, so that the bed-section C settles down into position back of the housing-member 9 and in collapsed relation with respect to the support-

ing-frame C'. The slideable frame C' may then be shoved rearwardly until the front housing-member 9 enters the space beneath the longitudinal member 2 of the main frame.

The foregoing detailed description has been given for clearness of understanding only, and no unnecessary limitations should be understood therefrom, but the appended claims should be construed as broadly as permissible, in view of the prior art.

What I regard as new, and desire to secure by Letters Patent, is:

1. A sofa-bed comprising a main frame, a rear bed-section mounted therein and adapted to serve as a seat, guides mounted in said frame at a distance below said rear bed-section, a horizontal slideable frame mounted in said guides, links mounted on said horizontal frame, a front bed-section having a frame equipped with slides mounted on said links, a link connecting said last-named frame with said slideable frame and equipped with an arm adapted to serve as a leg, and a counterbalancing spring connecting said arm with said slideable frame.

2. In a sofa bed having a forwardly slideable frame carrying a bed section, means for raising said bed section and supporting the same in raised position, said means including links pivotally mounted on the end members of the slideable frame and adapted to swing forwardly and upwardly in raising the bed section, two of the links on opposite ends of the frame equipped with extensions joined by a handle lying over the body section, slides carried by the bed section and pivotally connected with the links, and links connecting the slides.

CHARLES R. HULTGREM.
